UNITED STATES PATENT OFFICE.

GEORGE L. McCARTHY, OF RYE, NEW YORK.

DESIGN FOR A PACK OF PLAYING-CARDS.

59,761.

Specification for Design.

Patented Nov. 22, 1921.

Application filed September 1, 1921. Serial No. 497,715. Term of patent 14 years.

To all whom it may concern:

Be it known that I, GEORGE L. McCARTHY, a citizen of the United States, and resident of Rye, county of Westchester, State of New York, have invented a new, original, and ornamental Design for a Pack of Playing-Cards, of which the following is a specification, reference being had to the accompanying drawing, forming part thereof, which drawing is a face view showing all the cards of a complete deck of cards, illustrating my new design.

I claim:

The ornamental design for a pack of playing cards, as shown.
